UNITED STATES PATENT OFFICE

FRIEDRICH JENSEN, OF HANOVER, GERMANY

SYRINGE

Application filed February 7, 1931, Serial No. 514,236, and in Germany January 22, 1927.

This invention relates to improvement in vaginal syringes.

Heretofore such syringes have comprised mainly a fluid-conducting tube terminating in a multi-orificed nozzle and carrying a bell-shaped plug or shield provided with an opening through which the spent flushing fluid can run off. This run-off opening consists of a straight or curved passage of narrow bore which is difficult and expensive to form and which is open to the drawback that it can only be hygienically cleaned and kept clean by the use of brushes or other devices which fit very accurately and require to be operated with great care. Again, the formation of the nozzle with a plurality of orifices represents an unnecessary expense which renders cleaning difficult or next to impossible.

There are also known constructions in which the run-off opening is formed centrally of the plug around the tube. This arrangement necessitates, however, exact fitting of the several parts so that the construction is rendered expensive on account of the complicated arrangement, and the opening can only be cleaned after the parts have been taken apart—an operation which requires care and is likely to be omitted, notwithstanding that thorough cleaning is absolutely essential if the device is to be kept free from germs.

The present invention has for its object to construct a vaginal syringe with the simplest possible means, which can be manufactured cheaply and which can be kept cleaned in the simplest possible manner.

This object is realized in respect that the orificed head of the fluid-conducting tube is provided with a single orifice which can be much more easily formed and kept clean than a multi-orificed head irrespective of whether the orifice is large or small. The run-off opening at the junction of the supply tube and the plug is constituted by one or more open-topped channels in one of the said parts. Such channel can be formed either in the outer wall of the tube or in the wall of the bore formed in the plug for passage of the tube. In either case the channel or channels

is or are fully exposed after the tube is withdrawn from the plug so that there is no obstacle to thorough hygienic cleaning without the employment of special cleaning instruments. If such open channel is formed on the tube itself, the plug will be formed with only a hole for passage of the tube. If, however, the open channel is formed in the plug, the wall of the tube will be smooth. When the tube is fitted to the plug the channel presents a passage through which the spent fluid runs off.

At least one channel may be formed in the tube and at least one channel may also be formed in the plug.

As the run-off opening is located in either case close to the tube in the use of the syringe the spent fluid runs along the tube and would run along the hose or the like for supplying the tube with fluid. There is slipped on to the tube a simple rubber ring which causes the fluid to drip off at this point.

In the accompanying drawings there are illustrated two embodiments of the invention.

Fig. 1 is a longitudinal section and Fig. 2 a transverse section of a construction in which the open channel is formed in the wall of the tube.

Fig. 3 is a longitudinal section and Fig. 4 a transverse section of a construction in which the channel is formed in the hole in the plug serving for passage of the tube.

The same reference numerals denote similar parts in the several figures.

In the form shown in Figs. 1 and 2 the plug 1 has a single hole which receives the tube 3 the rear end of which is formed with a bulbous portion 4 or equivalent for connection to a hose or other device for the supply of fluid.

The front or delivery end of the tube is formed with a single delivery orifice 5 which can be produced more readily and more cheaply and kept cleaner than the plurality of orifices provided in the nozzle heretofore used. The spent fluid runs off through the passage 6, which, as shown in Figs. 1 and 2, is constituted by an open channel formed in the outer wall of the tube and extending over

at least the length of the plug. In this form the plug has only the smooth hole 2 for reception of the tube.

In the construction according to Figs. 3 and 4 the open channel 6' is formed in the hole of the plug so that the tube has a smooth outer surface.

Depending on the nature of the material constituting the plug and tube (soft or hard rubber, glass, celluloid, or the like), the channels 6 or 6' may be applied to or formed integral with the tube, or the bulb. If so desired, the stock from which the tube is formed may be channelled so that the tube cut off the said stock will have a channel extending over its entire length.

In order to cause the spent fluid to drop off the end of the tube connected to the hose, there is slipped over the latter a rubber ring 7 which may also serve to retain the hose on the bulb 4 as shown in Fig. 3.

Instead of a single open channel, such as the channels 6 or 6', there may be provided several such channels in the wall of the tube or in the wall of the hole of the plug. It is desirable that the cross-sectional area of the run-off opening or openings be less than the total cross-sectional area of the delivery orifice in the tube so that super-pressure may be set up in the vagina during the use of the syringe and a better flushing effect be obtained.

What I claim as my invention and desire to secure by Letters Patent of the United States, is:

1. A syringe comprising a plug having a passage through it and a tube extending through the passages in the plug, the tube having on its outer face a longitudinally extending groove forming a longitudinally extending straight channel open at both ends and greater in length than the length of the plug, the plug being longitudinally shiftable upon the tube to a position where it will entirely close one end of the channel or partially close this end.

2. A syringe comprising a plug of soft rubber tapering toward one end, a tube of hard rubber extending longitudinally through the plug, the plug being shiftable upon the tube longitudinally whereby the plug and tube may be removed from engagement with each other, the confronting faces of the plug and tube being formed to provide a longitudinally extending groove constituting a straight reflux channel opening upon the inner and outer faces of the plug.

In testimony whereof I have hereunto affixed my signature.
